PHONOGRAPH STRUCTURE

Henry T. Roberts, Chicago, Ill., assignor to J. P. Seeburg Corporation, Chicago, Ill., a corporation of Illinois

Application March 21, 1938, Serial No. 197,075

1 Claim. (Cl. 312—8)

An object of my invention is to provide a phonograph structure particularly of the commercial type for use in taverns and the like and which are often subject to rough usage, the structure being designed to effectively withstand such usage.

A further object is to provide a phonograph structure which can be readily operated by those desiring music and which can be readily manipulated by a serviceman for changing records when desired. In this connection I provide a cabinet which is so designed that changeable indicia elements are closely adjacent and in a convenient position relative to the record changing compartment and the record changing compartment can be fully opened to facilitate record and indicia changing operations.

A further object is to provide a phonograph of the type having a plurality of records which can be selected as desired, various parts of the mechanism being so arranged that the selecting keys are positioned relative to the indicia elements for the various records in the phonograph cabinet so that the two are closely associated visually and accordingly the device can be operated conveniently without the necessity of looking at one place for the indicia and then having to select the record at a point spaced so far from the indicia elements that there is likelihood of inaccuracy in the selection after the indicia and its corresponding number for the key have been noted.

Still a further object is to provide a door for the phonograph mechanism which has a loud speaker mounted thereon so that when the door is opened, access can be had to the speaker as well as to the internal mechanism of the cabinet.

Another object is to provide illuminating means for ornamenting the front of the cabinet which consists of elongated light bulbs spanning a door in the cabinet front and to provide for the bulbs combined ornamental molding members and protectors which prevent access to the bulbs from the front of the cabinet but permit access thereto from the back of the door when the door, which is of composite construction, has one part thereof open relative to the other part thereof.

With these and other objects in view my invention consists in the construction, arrangement and combination of the various parts of my phonograph, whereby the objects contemplated are attained, as hereinafter more fully set forth, pointed out in my claim and illustrated in the accompanying drawings. Although

the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawings, in which:

Figure 1 is a perspective view of the upper portion of a phonograph structure embodying my invention and showing the record compartment open for the purpose of changing records.

Figure 2 is a perspective view of the phonograph structure showing it in closed position.

Figure 3 is a sectional view of the front thereof showing the door for the front in open position.

Figure 4 is an enlarged perspective view of a portion of Figure 3 showing only part of the door open for gaining access to illuminating elements of the door.

Figure 5 is an enlarged sectional view on the line 5—5 of Figure 2.

Figure 6 is an enlarged sectional view on the line 6—6 of Figure 2 showing part of the door open in dot and dash lines.

Figure 7 is an enlarged vertical sectional view on the line 7—7 of Figure 2 showing hinge connections of the door in the cabinet; and

Figure 8 is an enlarged sectional view on the line 8—8 of Figure 2 showing a plan view of the door and showing the complete door open by dot and dash lines.

On the accompanying drawings I have used the reference character C to indicate generally a cabinet. The cabinet C has therein a record changing compartment 10. The compartment 10 extends to the top of the cabinet and provides space in which a serviceman can conveniently change the records on a plurality of record supporting devices 12. Within the cabinet C phonograph mechanism is provided which includes a sound pick-up arm 13 and a turntable 14. The turntable 14 is adapted to rise from the position illustrated after one of the record supporting plates 12 is moved to position 45. Under the sound pick-up arm 13 so as to pick up the record from the support and engage it with the needle 15 of the arm 13. This is a usual type of commercial phonograph and of course there is considerable mechanism to effect automatic operation but such mechanism forms no part of my present invention.

A cover 16 is provided for the record changing compartment 10 and the cover extends normally across the top of the compartment as 55

shown in Figure 2, and has a portion 17 to cover the front of the compartment. The cover 16 is adapted to be locked in closed position by a lock 18 engaging in a striker plate 19.

5 In front of the record changing compartment 10 is a shelf 20. On the shelf 20, supporting walls 22 are provided to receive indicia elements 23 to indicate the different records supported by the supporting plates 12. These indicia elements have corresponding indicia 1, 2, * * * 19 and 20, as shown in Figure 1, which serve as indicators for the different records supported by the supporting plates 12. On the front of the shelf 20 there is an escutcheon plate 24 having likewise thereon indicia 1, 2, * * * 19 and 20 for different record selecting keys 25. The plate 24, it will be noted, is closely adjacent the top of the shelf 20; the selecting keys 25 are therefore closely associated visually with the 20 indicia elements 23. This makes it comparatively easy for the operator of the machine to select an indicia element 23 and then note the indicating number corresponding thereto and depress the proper key 25 for bringing the 25 responding plate 12 to position for changing its record without having to move his eyes very far from the top of the shelf to the keys 25. Also, the selection can be made while in a standing position and it is unnecessary to note the indicia 30 element in one position and then change positions in order to operate the keys.

The indicia elements 23 are normally covered by a frame 231 having a transparent member 232 over the indicia elements. The frame 231 is 35 hinged as at 233 to supporting lugs 234 extending from and supported by the cabinet C. The frame 231 may be swung to the dotted position shown in Figure 1 to permit access to the pockets 22 and when the frame 231 is swung back to closed 40 position, it is retained against unauthorized opening by the lid 16 when it is in closed position.

I provide a door for the front of my cabinet comprising an inner door element 26 secured to an outer frame 27 and an inner frame 28. The 45 outer frame 27 is hinged to a sill 29 and a head jamb 30 of the cabinet C by bolts 31. These bolts are located adjacent the right side of the door element 26 and the right side jamb 32 of the cabinet is cut away as indicated at 33 in 50 Figure 8 to permit swinging of the door as to the position shown by dot and dash lines in this figure without interference of the side jamb with the door.

The inner frame 28 is hinged as by hinges 34 55 to the outer frame 27. The inner frame is normally retained in position by screws 35 (see Figures 3 and 8). When these screws are removed, the inner frame can be swung out to the position shown in dot and dash lines in Figure 6. This 60 position is shown by solid lines in Figure 4.

The door element 26 is adapted for supporting one or more loud speakers 36 and 37 as shown in Figure 3. The door structure is normally retained in position by a lock rod 38 coating with 65 a clip 39 on the door. This rod is normally retained in lowered position by a key-actuated cam 40 shown in Figure 1. Access can be had to the cam for insertion of a key therein to rotate the cam only after the lid 16 has been raised.

70 The inner frame 28 is adapted to support il-

luminating elements 41. These are preferably elongated electric light bulbs and are provided at their ends with terminal members 42 adapted to enter terminal socket members 43. The illuminating elements 41 are provided for making the 5 phonograph cabinet ornamental and this raises the problem of suitably protecting the bulbs 41 against injury. I accomplish this and at the same time enhance the appearance of the cabinet by the use of ornamental mold members 44 which 10 are of translucent material and curved to cover the outer surfaces of the bulbs 41.

Access can be had to the bulbs for removing them by opening the inner frame 28 as shown in Figure 4. The mold members 44 are supported 15 relative to the side members of the inner frame by being countersunk at their ends therein. The side members are routed as indicated at 45 (see Figure 6) to receive the ends of the molding members. Additional ornamental members 46 20 are illustrated received in sockets 47 of the side members of the frame 28. These are held against rotation by set screws 48.

I have provided a commercial phonograph structure which can be readily operated by the 25 serviceman when changing records without the necessity of working in an uncomfortable position. The entire top and front of the record changing compartment can be opened so that there is no interference with his movements during the record changing operation. The shelf 20 being located directly in front of the record changing compartment makes it easy to change the indicia 23 with a minimum possibility of 30 making mistakes of correlating the indicia and records while changing the records. The bulbs 41 are effectively protected against injury yet when necessary they can be readily removed by opening the outer portion of the door on the front of the cabinet and leaving the inner portion remaining closed. When access to the loud 35 speaker or other mechanism within the cabinet is desirable, the entire door can be opened. When the parts are in closed position, the single lock 40 45 is the only one exposed to view.

Some changes may be made in the construction and arrangement of the parts of my phonograph without departing from the real spirit and purpose of my invention. I therefore intend to cover by my claim, any modified forms of 50 structure or use of mechanical equivalents, which may be reasonably included within their scope.

I claim as my invention:

In a phonograph structure, a cabinet, a record changing compartment therein extending to the 55 top thereof, a shelf in front of said record changing compartment and extending in the horizontal direction along the compartment, means in said shelf to receive indicia elements for the different records in said cabinet, a transparent 60 cover element for said indicia elements, said cover element being hinged to said cabinet and a cover for said record changing compartment terminating on the back edge of said transparent cover element when the cover element and cover are in 65 closed position whereby when said cover is in said position said hinged cover element is retained thereby against being swung to uncovering position relative to said indicia elements.

HENRY T. ROBERTS. 70
